F. MANKEY.

SURFACE ORNAMENTATION OF WALLS, &c.

No. 16,243.

Patented Sept. 8, 1885.

UNITED STATES PATENT OFFICE.

FREDERICK MANKEY, OF WILLIAMSPORT, PENNSYLVANIA.

DESIGN FOR SURFACE ORNAMENTATION OF WALLS, &c.

SPECIFICATION forming part of Design No. 16,243, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and

5 original Design for Surface Ornamentation of Walls, &c., of which the following is a specification, reference being had to the accompanying photograph, forming part hereof.

My design is intended for the ornamentation 10 of surfaces; and it consists in the hexagonal pyramidal elevations A, formed upon the surface of a panel, for example, disposed in rows longitudinally said panel, and alternating with two trilateral pyramidal elevations, B and C.

15 The elevations B and C are placed point to point, as shown, and are separated from the adjacent elevations A by channels D E, formed diagonally across the panel. The adjacent row of similar elevations is separated by a longi-

tudinal channel, F, and the elevations A of 20 one row alternate with the elevations of the next row.

I claim—

The design for surface ornamentation of 25 walls, &c., such as herein shown and described, consisting in hexagonal pyramidal elevations A, disposed in rows longitudinally the surface, and between said pyramidal elevations two trilateral pyramidal elevations, B C, and channels D and E, extending diagonally across said 30 surface and separating said elevations, and channels F, extending longitudinally said surface and separating said longitudinal rows.

FREDERICK MANKEY.
